SEALED COMPRESSOR

William W. Higham, Detroit, Mich., assignor to
 Universal Cooler Corporation, Detroit, Mich., a
 corporation of Michigan

Application April 10, 1940, Serial No. 328,849

13 Claims. (Cl. 230—206)

This invention relates to a refrigerant compressor, and it is concerned particularly with a compressor of the so-called sealed type wherein the motor and compressing mechanism are located within a sealed housing.

It is the aim of the invention to provide a sealed compressor unit which embodies an improved structure capable of efficient trouble free operation. To this end, there are included among the objects of the invention the provision of a novel lubricating system for lubricating moving parts of the mechanism; the provision of a structure wherein such parts as the motor bearings, reciprocating parts such as pistons and connecting rods, and thrust bearings are located in a single chamber which incorporates no partitioning wall between portions of the chamber. A further object is the provision of an arrangement which, although parts are disposed within a sealed chamber, the valves associated with the pumping mechanism are readily accessible for service operations, and are so arranged that access may be had thereto without disturbing the remaining mechanism within the sealed unit. Also, an arrangement is provided wherein the lubricating oil is cooled during the operation of the mechanism, together with an arrangement which prevents lubricating oil from being forced back into the refrigerant line in the event high pressure is developed within the sealed unit. The arrangement also provides for proper lubrication with a wide variation of oil level in the unit, with the result that even if there should be a loss of considerable of the lubricating oil, the unit will operate satisfactorily. These and other objects of the invention will be more readily understood and appreciated as the detailed description is considered in conjunction with the accompanying drawings which show devices for carrying out the invention.

Fig. 1 is a vertical section taken through a compressor constructed in accordance with the invention showing some parts in section and some in elevation.

Fig. 2 is a cross sectional view taken substantially on line 2—2 of Fig. 1 showing the web structure and some refrigerant passageways.

Fig. 3 is a sectional view taken through the lower portion of the compressor substantially on line 3—3 of Fig. 1.

Fig. 4 is a detailed view showing the pump arrangement for the lubricating system with the gasket in location and taken substantially on line 4—4 of Fig. 1.

Fig. 5 is a view similar to Fig. 4 with the gasket

removed and taken substantially on line 5—5 of Fig. 1.

Fig. 6 is a sectional view taken substantially on line 6—6 of Fig. 5.

Fig. 7 is a view taken substantially on line 7—7 of Fig. 5.

Fig. 8 is an enlarged detail section of a part of the lubricating pump structure taken substantially on line 8—8 of Fig. 5.

Fig. 9 is a partial view illustrating the rotor structure and looking in the direction of line 9—9 of Fig. 1.

Fig. 10 is a detail view showing an inlet valve for the compressor.

Fig. 11 is a sectional view taken substantially on line 11—11 of Fig. 1 showing other valve structure.

Fig. 12 is a detailed sectional view of the outlet valve of the compressor structure.

Fig. 13 is a side elevational view of the unit with part of the cover dome cut away to show electrical connections and also illustrating a mounting.

Fig. 14 is an enlarged sectional view showing a mounting.

The compressor unit takes the form of a body, which is preferably a casting, as generally illustrated at 1 and which is open at one end but which is closed by a dome 2, and which may be of suitably fashioned sheet metal. This dome, as shown in Fig. 13, has suitable terminals 3 passing therethrough for the supply of electric current to the motor. The dome is secured to the casting as by means of bolts 4.

The casting adjacent its open end has an interior machined surface into which the stator of the motor is press fitted, the stator being shown at 6. The rotor of the motor is illustrated at 7, and it is provided with apertures 8 extending through its central portion. The apertures 8 are inclined in such a direction relative to the direction of rotation of the rotor that they act in the manner of a pump to accentuate flow of the refrigerant therethrough.

The end of the casting opposite the dome has a closing wall 10 arranged to receive a bearing 11 for a crank-shaft generally indicated at 12. The shaft has an end portion 13 journaled in the bearing; it has a throw 14, and the rotor 7 secured to the upper end of the shaft as indicated at 15.

The body in its intermediate portion is formed with an open web 16 having apertures 17 therein as indicated, and its central portion is recessed for the reception of a bearing support 18 for a

bearing 19 in which an intermediate portion of the shaft is journaled. This support is secured to the web by suitable means such as cap screws as indicated. Connecting rods 20 are mounted upon the throw 14 of the shaft and are connected to pistons 21. The form of compressor shown embodies two cylinders, although the compressor may be made with but one cylinder and with more than two cylinders. The crank-shaft is provided with a single throw, and the cylinders are disposed substantially diametrically opposite each other. The compression action of the two cylinders function in sequence. The lower piston rod is designed to rest upon a free ring or bushing 23, and the connecting rod is counterbalanced as at 24 to bring its center of gravity within the periphery of the bushing 23 to eliminate any tipping action of the connecting rod. The result is a self-supporting rod with no side thrust on the piston. The upper connecting rod is similarly counter-balanced and it rests upon the lower connecting rod with no resulting side thrust on its piston. In this connection it will be understood that the unit is designed to operate in an upright position, as shown in Figs. 1 and 2.

Before proceeding with the lubricating system, it is thought that it would be well to trace the flow of refrigerant through the unit. The body casting is provided with a recess 25 over which an inlet fitting 26 is to be bolted, and which fitting includes a shut-off valve which may be closed by the turning of the valve piece 27 normally closed by a cap 28. A gasket is disposed between the inlet fitting and the body, and it is preferably provided with a screen 30. A tube 31 leads from the chamber 25 to a point near the bottom and below the normal level of the oil as indicated. The refrigerant gases entering at 31 have free access to the entire interior of the unit and can pass upwardly through the openings 17 in the web 16 and through the openings 8 in the rotor to the top of the unit. From this upper portion of the unit the gases pass to the two cylinders and a description of the passageways to one cylinder and through the same will suffice for both cylinders, as they are duplicates and have the same reference characters applied to like parts. A conduit 32 opening in the upper portion of the unit communicates with a passage 33, which joins with a passage 34. From this point the gases pass into the cylinder 22, are compressed, and then pass from the cylinder in compressed condition into a passageway 35 which joins with a passage 36 and which extends to an outlet chamber 37. An outlet valve 38 is bolted to the body casting over the chamber 37 and this valve may be closed if desired by means of operating the valve piece 40.

The valve structure for controlling the flow of refrigerant to and from each cylinder is shown in Figs. 10, 11 and 12. A reed valve member 41 is located on the body casting as by means of pins 42 and over this reed is positioned a plate 43, and over the plate is positioned a cap 44 having a dividing partition 45. Passageway 34 leads to an aperture 46 in the plate 43 and into chamber 47 of the cap. The plate 43 has an aperture 48 leading from the chamber 47 to the cylinder. The reed valve opens the port 48 for the inlet of refrigerant as the piston moves the section stroke and closes the port 48 on the compression stroke. The plate 43 has an outlet aperture 49 leading to chamber 50 which joins with the passageway 35 through a port 51 in the plate 43. The outlet

valve for the port 49 is shown in Fig. 12, and it is mounted upon the plate 43. It takes the form of a flexible sheet metal valve 52 supported by cap screws 53 with enough looseness on at least one pin so that the valve may be flexed for the opening of the port 51. A curved and stronger strip or plate of metal 54 overlies the valve 52 but is spaced from its intermediate portion and is held against the ends of the valve by a spring 55 which is stronger than the valve plate 52. In normal operation there is sufficient clearance between the center portion of the valve 52 and the member 54 so that only the valve 52 flexes, but in the event of a heavy charge or slug of oil the valve 52 and plate 54 may shift bodily away from the plate 43 against the action of the stronger spring 55. A seal in the form of a wire 56 may hold the screws from rotating following an initial set at the factory.

As pointed out above, the unit is designed to operate in an upright position, and accordingly a thrust bearing arrangement is provided at the lower end of the shaft. This thrust bearing arrangement also embodies a rotary pump. As shown in Fig. 6, the bearing 11 is just a little short of extending entirely through the bottom portion of the casting and a member 60, which may be a bronze disc, is associated with the end of the shaft and it takes the thrust load in that it bears upon the closing tap 61 secured to the body with an intervening gasket 62, as indicated. This bronze disc is eccentrically located on the bottom of the shaft as by means of two pins 63 and the eccentricity is just about the thickness of the bearing. Accordingly, the bronze disc functions within the confining wall of the aperture in the housing. The bottom of the housing is provided with three milled slots, one of which, as indicated at 64, connects to an oil inlet passage 65 in the casting; one of which, as at 66, connects to an oil outlet tube 67. This tube is located in an aperture drilled in the casting and then its lower end is expanded as at 68 against the screw threads formed in the aperture to permanently set and locate the tube. The central milled slot 69 is provided with a follower 70 acted upon by a spring 71 positioned in part in a recess 72.

The gasket 62 has a laterally extending opening 73, which is positioned off the center line as shown, and embraces the inlet slot 64 and the slot 69, but seals off the outlet slot 66. Thus oil cannot be trapped back of the follower 70, as this space is connected to the inlet. Accordingly, as Fig. 4 is considered, bearing in mind that the direction of rotation is clockwise, the structure provides a rotary eccentric pump wherein oil is caused to flow into the low side through the slot 64 and is pumped out the high side through the slot 66, with the division maintained by the sealing follower 70 which reciprocates in frictional engagement with the periphery of the disc 60.

The bearing 11 is provided with a helical slot 80 which opens into the high side of the pump arrangement as indicated in Figs. 4 and 5 so that oil is also pumped into this helical slot and upwardly through the bearing 11 to provide lubrication at this point. The upper end of the slot 80 opens into a space 81 defined by the bearing ring 23, and the connecting rod has a passageway 82 leading to outlet ports 83 in its bearing surface. Accordingly, in the operation of the device, the eccentric pump causes a positive flow of oil up through the passageway 80, thus lubricating the bearing 11 and through the passage

ways 82 and 83, thus lubricating the connections between the throw of the crank-shaft and the connecting rods. Some escape of oil and splash of oil lubricates the surfaces between the ring 23 and the housing and one connecting rod and the abutting surfaces of the connecting rods.

Oil is pumped through the tube 67, and this tube passes upwardly through one of the apertures 17 as indicated, and discharges the oil. The web is provided with a recessed formation 85 which, in effect, forms a gutter into which the oil collects. The bearing support 18 has a passageway 86 which leads to the lower portion of the bearing 19, and the bearing 19 has a helical groove 87 which causes the oil to move upwardly as the shaft rotates to lubricate this location.

The pistons and their pins are also lubricated from this forced feed arrangement. It will be observed (Fig. 2) that the gutter 85 extends laterally on opposite sides, thus providing reservoir extensions 88 into which the oil flows. The ends of these extensions are elevated as at 89, and downwardly extending oil passages 90 are provided, continuations of which at 91 communicate to the cylinders. Oil thus flows into the cylinders and into the wrist pins which are hollow as shown and which are provided each with an oil passage 92 for lubricating the wrist pin journal. It might be said that the wrist pins are each held in position by a spring clip 93. The clip engages opposite ends of the wrist pin and one end is more or less keyed to the wrist pin and it projects into a recess in the piston as shown at 93a. Thus the wrist pin is held against axial movement and against rotary movement, and the oil hole 92 is thus held in a proper direction.

For the purpose of lubricating the valve structure, the passage 34 is formed to intersect both the passage 33 for the refrigerant gases and the oil passage 90-91. Dividing the oil and refrigerant gases is a plug 96 provided with a small tube 97. The flow of the refrigerant is indicated in Fig. 1, sets up sort of a Venturi action and some of the oil vapors are drawn through the tube 97 into the refrigerant. These oil vapors, and perhaps some small quantity of oil, is carried through the valve structure and into the compressed refrigerant line. This oil may pass through the system but is discharged back into the unit as the refrigerant enters through the pipe 31.

The compressor may be mounted in a suitable manner and the one shown comprises a flexible or vibration dampening mounting. The body casting may be provided with lugs 100 for the reception of supporting pieces having a plate 101 with a screwthreaded stud positioned in the lug and a body of rubber or equivalent material 102 having a plate 103 with a bolt or stud arranged to be secured to supporting brackets 104. The rubber body 102 is bonded to the plates 101 and 103.

The inlet for the refrigerant is also provided with a small aperture 99 connecting the inlet chamber 35 to the interior of the unit. This is a small bleed aperture. The major part of the refrigerant gases enter the unit through the pipe 31 to thus cool the oil. In the event, however, that unduly high pressures develop within the compressor unit for one reason or another, this pressure may bleed back into the inlet line through the bleed aperture 99 and thus will not force oil back into the line through the tube 31.

In the operation of the compressor expanded

refrigerant flows into the unit and is discharged into the oil by the tube 31. This sets up an agitation of the oil and it is thereby cooled. The refrigerant is drawn upwardly through the supporting web 16 through the rotor and down through the tubes 32. If any oil collects at the upper level around the stator 6, it may flow through the small apertures 32a and into the refrigerant line so that it is carried back into the lower part of the chamber. Refrigerant is drawn, as above explained, through the several passageways and is compressed and passes out through the outlet passages 36. The rotary pump positively pumps oil up through the helical groove 80 to lubricate the lower bearing and then up into the chamber 82 to lubricate the connecting rods. Oil is also positively pumped through the tube 67 and discharged into the gutter 85. This flows through passageway 86 into the helical groove 87 to lubricate the upper bearing. The oil is pumped upwardly by the action of the helical groove 87 and the turning of the shaft. The oil which flows through the outlets 90 moves downwardly and lubricates the piston and the piston wrist pins. The elevated portions 89 permit of collection of extraneous articles in the lower level of the gutter so that such particles may not flow through the passage 90.

All of the working mechanism, including the motor, the bearings, both upper and lower, the connecting rods and pistons, are disposed in a single undivided chamber. There is no partition or dividing means within the chamber. Any excess oil which is pumped into the gutter may merely flow over the same and back into the sump in the bottom of the body casting. Notwithstanding the fact that a sealed unit is provided, in that all working parts are in a sealed chamber, the valves are accessible for service or removal. This is done by merely closing the lines by the service valves 27 and 40 and then by detaching the valve structure which includes cap 44, plate 43 and the valves themselves. After repair or replacement, the service valves may be opened and the apparatus is again in condition to operate.

I claim:

1. In a refrigerant compressor of the sealed type, means forming a sealed chamber, a substantially vertically disposed crank-shaft in the chamber, a substantially horizontally disposed cylinder with a piston therein, a connecting rod substantially horizontally disposed and pivotally connecting the crank and piston, means supporting the end of the connecting rod which surrounds the crank for taking the vertical load thereof, and a counter-balancing weight on the connecting rod opposite the part which extends to the piston for placing the center of gravity of the connecting rod within the confines of the supporting means whereby the connecting rod is gravitationally stable to thereby eliminate gravity thrust on the piston.

2. In a refrigerant compressor of the sealed type, means forming a sealed chamber, a substantially vertically disposed crank-shaft in the chamber, a substantially horizontally disposed cylinder with a piston therein, a connecting rod substantially horizontally disposed and connecting the crank and piston, a ring positioned around the crank-shaft and supporting the connecting rod, a counter-balancing weight on the connecting rod substantially opposite its extension to the piston arranged to place the center of gravity of the connecting rod substantially within the

contour of the ring whereby the connecting rod is gravitationally stable on the ring.

3. In a refrigerant compressor of the sealed type, a body member, closure means forming a substantially sealed chamber, compressing mechanism within the chamber including a crank-shaft and a motor for driving the same, said crank-shaft being disposed on a substantially vertical axis, means forming a bearing for the lower end of the crank-shaft, means forming a bearing for an upper portion of the crank-shaft, a combined thrust and rotary pump member for the lower end of the crank-shaft for taking the vertical load and non-rotatably and eccentrically connected to the crank-shaft, means forming a housing for the thrust member, a spring pressed vane having a wiping contact with an edge of the eccentric thrust member whereby a rotary pump is formed, means for conducting lubricating oil to the inlet side of the vane, and a conduit connected to the other side of the vane and extending upwardly for discharging lubricating oil to the upper bearing.

4. In a refrigerant compressor of the sealed type, a body member, a closure member forming with the body member, a substantially sealed chamber, compressing mechanism within the chamber including a crank-shaft and a motor for driving the same, said crank-shaft being disposed on the substantially vertical axis, means forming a bearing for the lower end of the crank-shaft, means forming a bearing for an upper portion of the crank-shaft, a combined thrust and rotary pump member for the lower end of the crank-shaft for taking the vertical load and non-rotatably and eccentrically connected to the crank-shaft, means forming a housing for the thrust member, a spring pressed vane having a wiping contact with an edge of the eccentric thrust member whereby a rotary pump is formed, means for conducting lubricating oil to the inlet side of the vane, and a conduit connected to the other side of the vane and extending upwardly for discharging lubricating oil to the upper bearing, and a helical groove associated with the lower bearing of the crank-shaft and opening on the outlet side of the vane for the pumping of oil through the lower bearing.

5. In a refrigerant compressor of the sealed type, a body member, a closure member forming with the body member, a substantially sealed chamber, compressing mechanism within the chamber including a crank-shaft and a motor for driving the same, said crank-shaft being disposed on the substantially vertical axis, the body having an opening therein with a bearing for the lower end of the crank-shaft, the axial length of said bearing being less than that of the opening, means forming a bearing for an upper part of the shaft, a combined thrust and pump member non-rotatably and eccentrically secured to the lower end of the shaft and operating in said opening at the end of the bearing whereby the walls of the opening form a pump housing, a shiftable vane wiping the edge of the thrust member, whereby a rotary pump is provided, an inlet for lubricating oil on one side of the vane, an outlet for oil on the other side of the vane, and a conduit extending from the outlet upwardly and arranged to discharge oil for the lubrication of the upper bearing.

6. In a refrigerant compressor, a shaft arranged to run substantially on a vertical axis, a combined thrust bearing and pump member in the form of a disc non-rotatably and eccen-

trically secured to the lower end of the shaft, supporting means under the disc for taking the vertical load of the shaft, means forming a housing for said member, a shiftable vane for wiping the edge of the eccentric member, means for introducing oil on one side of the vane, one or more outlets for lubricating oil on the opposite side of the vane, and means for conducting the lubricating oil from the outlets to parts to be lubricated.

7. In a refrigerant compressor, means providing a sealed chamber, a body member, an oil sump, formation in the chamber, said body having an opening therein, a bearing in the opening, a shaft journaled in the bearing and disposed substantially on a vertical axis, said bearing being axially shorter than the opening, a combined thrust disc and pump member eccentrically secured to the lower end of the shaft and operating in the opening at the end of the bearing, whereby the walls of the opening form a pump housing, said disc resting upon a portion of the body member to take the vertical load of the shaft, three slots in the body member and opening into said pump housing, a spring pressed vane in one slot arranged to wipe and follow the edge of the eccentric member, means for conveying oil from the sump to one of the side slots and constituting an oil inlet, the other side slot constituting an oil outlet, and means for conducting oil from the outlet to parts to be lubricated.

8. In a refrigerant compressor of the sealed type, a body member having a bottom enlargement provided with a bearing, a shaft having its lower end journaled in the bearing and arranged to run substantially on a vertical axis, said shaft having a crank, a ring surrounding the crank and resting upon the enlargement, said crank being positioned above the enlargement to form a space confined by the ring, a passage extending upwardly in the crank, one or more connecting rods on the crank, another passage extending to the surface of the crank, and means for pumping lubricating oil upwardly through the bearing into said space confined by the ring and upwardly in the passage in the crank and out through the other passage for lubricating purposes.

9. In a refrigerant compressor of the sealed type, means forming a substantially sealed chamber, a crank-shaft arranged to run substantially on a vertical axis, means forming a bearing for the lower end of the crank-shaft, a web structure in the chamber for supporting a bearing for an upper portion of the shaft, said web structure having a raised formation extending around the bearing forming a gutter, means for pumping oil from the lower part of the chamber upwardly and for discharging the same into the gutter, excess oil being adapted to overflow the gutter, a passageway in the bearing support leading from the gutter to the lower portion of the upper bearing, and a helical groove associated with the upper bearing for the movement of oil upwardly through the bearing for lubricating purposes.

10. In a refrigerant compressor of the sealed type, a body member, means forming a substantially sealed chamber, a horizontally disposed cylinder in the body member, inlet and outlet means for refrigerant, compressing mechanism including a motor and crank-shaft disposed within the chamber with the motor disposed in the upper part of the chamber and, with the

crank-shaft disposed substantially on a vertical axis, means on the body member above the cylinder and below the motor for supporting a bearing for the shaft, said supporting means including a gutter formation, means for pumping lubricating oil from the lower portion of the body upwardly and for discharging it into the gutter, and a passageway extending downwardly from the gutter and opening into the cylinder for the lubrication of the piston and cylinder.

11. In a compressor of the sealed type, a body member, means forming a substantially closed chamber, a motor and compressing mechanism in the chamber and including a cylinder and piston, an inlet for refrigerant, an outlet for refrigerant, inlet and outlet valves for the cylinder, a passageway for refrigerant gases leading from the interior of the unit to the cylinder, a lubricant passageway for feeding lubricant to an operating part, and means including a relatively small opening interconnecting the refrigerant passageway, and lubricant passageway, whereby movement of the refrigerant gases draws oil vapors through said relatively small opening for conveying the same to the cylinder valve mechanism for lubricating the same.

12. In a compressor or the like, a conduit for a fluid such as lubricating oil or the like comprising, a body member formed with an opening

having an enlarged part, the walls of the enlarged part having roughened surfaces, a tube extending in the opening and having a portion disposed in the large part of the opening and expanded therein with the roughened formation forming a corresponding and interfitting formation on the exterior of the expanded part to locate and hold the tube in position.

13. In a refrigerant compressor, means providing a sealed chamber, a body member, an oil sump formation in the chamber, said body member having a wall in which a shaft is journaled, an eccentric pump member on the end of the shaft, means forming a housing for the pump member including the wall and closure plate, three milled slots in a housing member and leading into the housing, one side slot being connected to an oil inlet, one side slot to an outlet and the intermediate slot having a vane positioned therein for wiping the edge of the eccentric pump member, a gasket between the wall and the plate and formed with an opening which substantially bridges the inlet slot and the intermediate slot to form a communication between the inlet slot and the back of the vane to prevent trapping of oil in the intermediate slot back of said vane.

WILLIAM W. HIGHAM.
